(57) **CLAIM**

The ornamental design for a window component extrusion, as shown and described.

DESCRIPTION

FIG. 1 is a perspective view of a window component extrusion according to the present invention;

FIG. 2 is a left side view of the window component extrusion of FIG. 1;

FIG. 3 is a right side view of the window component extrusion of FIG. 1;

FIG. 4 is a rear view of the window component extrusion of FIG. 1;

FIG. 5 is a front view of the window component extrusion of FIG. 1;

FIG. 6 is a top view of the window component extrusion of FIG. 1; and,

FIG. 7 is a bottom view of the window component extrusion of FIG. 1.

The broken lines shown in FIGS. 1 and 6 illustrate portions of the window component extrusion that form no part of the claimed design.

The window component extrusion is shown with a wavy edge in FIGS. 1 and 4-7 to note that the window component extrusion may be longer than as shown. Any portion of the window component extrusion which has not been shown forms no part of the claimed design.
